SUPPLEMENTAL PROTECTIVE CLOSURE

William N. Booth, Detroit, Mich.

Application July 2, 1937, Serial No. 151,714

2 Claims. (Cl. 189—79)

This invention relates to movable and removable protective closures, of a supplemental character, for windows, doorways and other openings of buildings.

It is common practice, when a house or other building is to remain unused for a considerable period of time to apply some form of protective covering over all openings, especially those which are glazed. A common expedient is simply to nail boards over such openings, although these not only present an unsightly appearance, but to some extent permanently deface the building because of the nail holes which are formed.

It is often desirable to arrange for airing such a temporarily closed building at suitable intervals, which is of course both troublesome and a cause of further disfigurement of the building, if boards must be removed and replaced.

The present invention aims to provide means, especially adapted for use with steel sash, possessing all of the advantages of previously known supplementary closures of the character indicated, adapted to protect the glass and the contents of the building and shield furnishings against the fading effects of sunlight, of stronger and more secure character than previously known protecting means, and which is weather, vermin and dirt proof, irremovable with ordinary tools when locked in place, yet presents a much neater appearance.

A further object is the provision of such protective covering means which is movable with the sash or frame by which it is carried, so that windows may easily be opened (although only from the inside), as for airing, without removing or disturbing the protecting means.

Another important object of the invention is the provision of such supplemental protecting means for steel sash which may be readily applied and removed when the sash is open, but is securely held in place and irremovable when the window is locked.

Other objects and advantages will be apparent from the following description, wherein reference is made to the accompanying drawings illustrating a preferred embodiment of my invention and wherein similar reference numerals designate similar parts throughout the several views.

In the drawings:

Figure 1 is a perspective view of a conventional steel sash assembly of a well known variety, showing a window partly open and provided with a protecting cover formed in accordance with the principles of this invention, the cover being shown slid partly over the window but not in its fully

applied position, and being also shown in another dotted line position removed from the window but aligned therewith and ready to be slid thereover.

Figure 2 is a perspective view of the rear face of the protecting cover element, removed from the window.

Figure 3 is a horizontal sectional view of the sash and protecting cover, taken substantially on the line 3—3 of Figure 1 and looking in the direction of the arrows, showing the cover slid over the window but not locked in place.

Figure 4 is similar view showing both the protecting device and window in their locked and closed positions of use, and

Figure 5 is a vertical sectional view, partly broken away, taken substantially on the line 5—5 of Figure 1, looking in the direction of the arrows.

Referring now to the drawings, reference character 10 designates a window frame adapted to be set in a casement (unshown), or supported in any suitable manner. The window frame carries a swing sash frame 12, which is shown as operable by a hand crank 15 and adapted to be secured tightly in closed position by locking means 17. These portions, as well as the glazing, muntins, and other structural features of the sash itself may of course be varied as desired and are intended to be represented only diagrammatically, the present invention concerning itself with the protecting means rather than the window construction.

The swinging sash 12 is provided with an outwardly extending marginal flange 14 which, when the window is closed and locked, is tightly clamped against the face of the frame member 10. The hinging means is shown as comprising a pair of outwardly projecting pivotally connected arms 18—19, the former carried by the frame and the latter by the sash. A bracket portion 16, secured to the face of the sash in the hinged corners, serves to fasten the sash to the hinge arms 19.

The protecting element comprises a sheet metal cover member 20 having all four of its edges marginally over-bent to embrace and retain it upon the flange 14 of the sash. The top and bottom over-bent retaining flanges of the cover member are designated 21, and as best appear in Figure 5, these are so spaced as to fit snugly but slidably over the sash flange portions. Retaining portions 21 terminate short of the hinged edge of the cover, and at the upper and lower hinged corners unflanged embossed sections 25 are formed to provide clearance for the hinge brackets 16. The hooked retaining flange 22 which

extends along that edge of the cover which overlies the hinged edge of the sash, also terminates short of the embossed areas, as shown in Figure 2. The similarly hooked retaining flange portion 23, for the free edge of the swinging sash, overlies the sash flange to a somewhat greater extent, for a purpose which will presently appear.

The cover is placed upon the window by fitting the cover flanges 21 over the sash flange 14 (top and bottom, with the window positioned as shown in the drawings), and sliding the cover from the free edge of the swinging window entirely thereover and until the retaining portion 22 lies beyond and is free of the hinged edge, as shown in Figure 3. For this purpose, the width of the cover member will be seen to exceed the width of the window sufficiently to allow the portion 22 to so clear the hinged edge when the cover is slid over the window as far as it will go. The overhanging portion 23 which embraces the free edge, however, is of such length that when the cover is again slid outwardly in a direction away from the hinged edge, to engage the portion 22 behind flange 14 along the hinged edge of the sash, the flanged portion 23 remains in overengaged relation with the free edge of the sash, as shown in Figure 4 (in which view the window is also shown closed and locked).

A certain amount of flexibility is provided by the fact that the top and bottom overbent holding and slide flanges 21 do not extend entirely to the hinged edge. The cover material is thereby able to bend somewhat about an axis parallel to the flange 22 and located at approximately the rear ends of the flanges 21, during application and removal of the cover, allowing flange 22 to freely snap over the hinged edge of the sash. When the cover is moved in the fully applied position in which it is shown in Figure 4, and the window is closed and pulled tight by the locking means, the flanges 21, 22, 23 are tightly clamped between the sash and the frame, preventing removal of the cover.

The only requisite to convenient application of my improved covering means will be seen to be a window (or door) having marginal portions over which the retaining flanges may be fitted before closure thereof. The retaining flanges, upon one or more sides, might of course be discontinuous, and in the form of fingers, although I prefer merely to overbend the edges of the material in the manner shown. Creasing the cover material slightly, in the manner indicated at 33, somewhat stiffens it as well as imparting a finished appearance, which may be heightened further by painting or finishing the covers to match the material or trim of the building. The windows may be opened and closed as many times as desired without danger of dislodging the installed covers, exactly as if they were not present, and it will also be recognized that the covers may be most economically produced of sheet metal, galvanized iron or the like.

The locking means 17 should of course be arranged to draw and hold the window tightly inward against the face of the frame and the interposed retaining flanges of the cover.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims. 5

What I claim is:

1. In combination with a substantially rectangular swingable closure having opposed outwardly extending marginal flange portions upon all four edges, a frame with which said closure is swingably associated, and locking means for the closure arranged to draw and hold said flanged portions tightly against said frame, a 10 supplementary cover member having overbent retaining portions adapted to overengage said flanges and bent inwardly toward each other over one face of the cover member, two of such opposed retaining portions forming grooves fitting relatively snugly and slidably over the correspondingly opposed flanges, the other opposed closure retaining portions being so arranged that the distance between the bottom of the groove formed by one thereof, and the nearest edge of the overbent portion of the other is greater than the extreme distance between the outside edges of the corresponding flanges of the closure overengaged thereby, the distance between the inturned edges of the second-named retaining means being less 30 than the distance between the outside edges of the mating closure flanges overengaged thereby, whereby two of said opposed retaining portions are engageable with the flanges only by sliding thereover, while at least one of said retaining portions is movable perpendicularly over the edge of its flange portion before being slid into engagement therewith. 35

2. In combination with a substantially rectangular swingable closure having opposed outwardly extending marginal flange portions upon all four edges, a frame with which said closure is swingably associated, and locking means for the closure arranged to draw and hold said flanged portions tightly against said frame, a 40 supplementary cover member having overbent retaining portions adapted to overengage said flanges, the overbent retaining portions upon two opposite sides of said cover member forming grooves slidably fitting over said flanges and ir- 45 removable therefrom perpendicularly of the plane of the closure, the other two sides of the cover member being provided with similarly overbent retaining portions, the distance between the inner edges of said last mentioned retaining portions 50 being less than the distance between the outer edges of the mating flanges, and the distance between the inner edge of one of said retaining portions and the bottom of the groove formed by the opposite retaining portion being greater 55 than said distance between the outer edges of the flanges, at least a portion of said cover member being flexible about an axis parallel to said last mentioned retaining portions. 60
